UNITED STATES PATENT OFFICE.

FREDERIC H. SCHOFF, OF QUINCY, ILLINOIS.

HINGE.

Application filed December 8, 1921. Serial No. 521,022.

To all whom it may concern:

Be it known that I, FREDERIC H. SCHOFF, a citizen of the United States, residing at Quincy, in the county of Adams and State 5 of Illinois, have invented certain new and useful Improvements in Hinges, of which the following is a specification.

This invention relates to an improved closure supporting device, and whereby a closure member such as a door may be detachably maintained in relative position with 10 respect to an opening.

The closure member supporting device is particularly well adapted as a spring hinge 15 upon screen doors, and in this specific application a hinged member is provided for attachment to the screen door, a supporting plate being provided for attachment to the jamb of a door opening, said hinged member 20 and supporting plate coacting to maintain the screen door in detachable relation in its opening.

A further object of the invention is the provision of a door hinge of the above described character, preferably formed of 25 sheet metal and so constructed as to permit the door to which the hinge is attached to be detached from its relative positioning in a closure opening in a facile manner and 30 without the use of screw drivers and other tools.

Other objects of the invention will be apparent during the course of the following detailed description.

35 In the accompanying drawing, forming a part of this specification, and wherein similar reference characters designate corresponding parts throughout the several views,

Figure 1 is a front elevation of the improved supporting device including a hinged member assembled to a supporting plate.

Figure 2 is a vertical cross sectional view, taken on the line 2-2 of Figure 1.

Figure 3 is a front elevation of a supporting plate.

Figure 4 is a front elevation partly in section of the improved hinged member.

Figure 5 is a plan view of the improved closure supporting device and showing the 50 relative arrangement of various parts.

In the drawing, wherein for the purpose of illustration is shown the preferred embodiment of my invention, the letter A designates the improved closure supporting device including a hinged member B and a supporting plate C

The hinged member B preferably comprises a pair of leaves 10 and 11, formed of a good grade of sheet steel. The leaf 10 has the upper and lower marginal edges 13 and 14 thereof bent outwardly at right angles to the plane of the sides, and which are provided with certain aligning apertures. The upper and lower marginal edges of the leaf 11 is bent forwardly in a plane substantially at right angles to the plane of said leaf 11 to provide the attaching flanges 15 and 16 having certain aligning apertures therein. The leaves 10 and 11 are adapted for assemblage in such manner that the aligning apertures in the attaching flanges 13 to 16 inclusive are in axial alignment for receiving a pivot pin 18 extending the length of the hinge B, and upon which the leaves 10 and 11 are relatively moved as an axis. The 70 leaf 11 is provided with an annular sleeve 20, extending for about three quarters of a circumference and which is adapted to provide a housing for the hinged spring 21, which is positioned axially of the pin 18. 80 The upper end of the spring 21 projects as at 22 to extend through an aperture or opening 23 in the upper end of the annular sleeve 20, and whereby the upper end of the spring 21 may be held in a definite relation. The 85 lower marginal edge of the annular sleeve 20 adjacent the leaf 10 is offset from the attaching flange 14 in order to provide a space 25 whereby the lower end 26 of the spring 21 may project therefrom for engaging the outer face 27 of the hinged leaf section 10, in order to maintain the lower end of the spring 21 in a determined relation and whereby upon relative movement of the leaf sections 10 and 11, the spring 21 will 90 be placed under compression, tending to force the leaf sections 10 and 11 into determined position. It is preferred that the rear longitudinal edge 29 adjacent the hinge 21 be so placed as to permit the housing 20 100 to clear the same, as the leaf sections 10 and 11 are relatively moved. 95

The leaf section 11 is provided with the ordinary bevelled circular apertures 31, adapted for receiving screw elements or the like, for attaching said leaf 11 to the door or closure member as is ordinarily the case. The other leaf section 10 is provided with the relatively large square upper and lower apertures 32 and 33 respectively, which are 110 in vertical alignment, the lower aperture 33 being disposed nearer to its attaching flange

14 than the upper aperture 32 is disposed to its adjacent attaching flange 13. Vertical slots 35 and 36 are cut inwardly from the upper and lower marginal edges of the leaf member 10 and are in alignment; the upper vertical slot 35 being relatively longer than the lower slot 36. It is preferred, that the slots 35 and 36 be disposed nearer the outer longitudinal edge 38 of the leaf 10 than the 10 apertures 32 and 33.

The supporting plate C is adapted for permanent attachment to the jamb or casing of a door opening or the like, and is formed of sheet material, such as steel, having the 15 bevelled circular apertures 40 therein for attachment of screw elements or the like to permit of the permanent attachment of the supporting plate C. The upper and lower substantially square tongues or hook members 42 and 43 respectively are struck from the body of the plate C. The hooks 42 and 43 are up-turned and having their ends 44 arcuated outwardly from the body of the plate C for a purpose to be subsequently set 20 forth. The space intermediate the inner surface 45 of each of the tongues 42 and 43, and the plane defined by the outer face of the plate C is sufficient to slidably receive the thickness of material of the leaf 10. The lower bight or connecting portions 46 of each of the tongues 42 and 43 are provided to serve as supporting shelves when the hinged member B is assembled to the 25 supporting plate C. It is preferred that the 30 dimensions of the tongues or hooks 42 and 43 be such as to permit their free entrance through the openings 32 and 33 of the leaf section 10; said hooks being in alignment to permit such connection of the hooks in the 35 apertures of leaf 10. The supporting plate C is furthermore provided adjacent the upper and lower marginal edges with the respective lugs 45 and 46 which project outwardly from the face 47 of the plate C, said 40 lugs 45 and 46 being in alignment, and of such dimension as to be slidably disposed in the aligning slots 35 and 36 above described.

In assembling the improved closure supporting devices A, any number of the same 50 may be provided for a door or other closure member. In the preferred assembly, the hinged members B are attached to the pivoting edge of the door in such manner that the leaf sections 10 project from the edge 55 of the door, as is ordinarily the case in assembling a hinged member. Each section 10 is provided with a co-acting supporting plate C, said supporting plate C being mounted upon the jamb or casing of an 60 opening.

It can thus be seen that the various parts of the closure supporting device may be properly assembled in permanent manner in their respective places. In order to attach 65 the door or other closure member to the sup-

porting plate C, it is merely necessary to so position the leaf sections 10 of the hinged members B as to permit the upper and lower hooks 42 and 43 to be inserted into the openings 32 and 33 provided in said 70 leaf section 10. Upon dropping of the door or other closure member, the leaf section 10 of each hinge member B will be dropped relative into the supporting hooks 42 and 43, and whereby the upper marginal edges 50 of each of the openings 32 and 33 will engage the supporting shelves 46 of the hooks 42 and 43, and whereby the hinge members B will be supported in proper position upon their respective attaching plates C. In this 80 position, the projecting lugs 45 and 46 will slide into the upper and lower slots 35 and 36 provided for them, and whereby all lateral sway or sagging of the hinged member B and plate C are prevented. It is to be noted that the projection 46 fits snugly within the slot 36, while on the other hand the relatively long upper slot 35 merely receives the lug 45 at its upper portion to prevent 85 lateral sway. This arrangement has been provided in order that the leaf section 10 may be easily assembled in the supporting plate B.

In order to detach a door or other closure member, it is merely necessary to lift 90 the same vertically and the leaf sections 10 will slide out of their respective supporting plates C.

Various changes in the shape, size and arrangement of parts may be made to the 100 form of the invention herein shown and described, without departing from the spirit of the invention or the scope of the claims.

I claim:

1. A closure supporting device comprising 105 a hinge member formed of a plurality of pivotally connected leaf sections, and a supporting plate, said hinge member and supporting plate having interengaging hook and socket means for suspending said hinge 110 member from said supporting plate, and interengaging lug and socket means for said hinge member and supporting plate adjacent the upper and lower marginal edges thereof to prevent lateral sway of 115 said hinge member and supporting plate.

2. A closure supporting device, comprising 120 a hinge member including a pair of leaf sections, one leaf section having upper and lower apertures struck therein and provided with upper and lower slots inwardly from the marginal edges of said leaf section, and a supporting plate having upper and lower outwardly struck tongues for detachable positioning in the upper and lower apertures of said leaf sections, said supporting plate having upper and lower outwardly projecting lugs for detachable positioning in the upper and lower slots of said section. 125

3. A closure supporting device comprising 130

ing a hinge member formed of a plurality of pivotally connected leaf sections and a supporting plate, said hinge member and supporting plate having detachably related 5 interengaging means for supporting said hinge member from said supporting plate including slots extending inwardly from the top and bottom marginal edges of a leaf section of the hinge member, and lugs 10 extending outwardly from the supporting plate adjacent the top and bottom marginal edges thereof for slidable engagement in the slots of the leaf sections to prevent lateral sway and accidental displacement of the 15 hinge member from the supporting plate.

4. A closure supporting device comprising a hinge member formed of a plurality of hingedly connected leaf sections and a supporting plate, said hinge member and

supporting plate having inter-engaging 20 hook and socket means for attaching said hinge member to said supporting plate, said hinge member having a relatively long slot provided inwardly from the top marginal edge of a leaf section thereof, and a relatively short slot provided inwardly from the bottom marginal edge of said leaf section in aligning relation with the relatively long slot provided inwardly therein, and lugs extending outwardly from the supporting plate adjacent to the top and bottom marginal edges thereof in aligning relation and adapted for slidable engagement in the slots of the leaf section to prevent lateral sway and accidental displacement of the hinge member with respect to the supporting plate. 30 35

FREDERIC H. SCHOFF.
